The accompanying photograph illustrates a face view of a carpet having my new design.

C is a bouquet, composed of the roses e, 15 branching leaves f, branch g, with leaves on one sprig and roses on the other, and branch k, with similar leaves thereon.

The figure D is composed of two roses with foliage and leafy sprays around them.

The figure a is composed of branching leaves and twigs and fern-like sprays.

d is a figure composed of star-like flowers and 30 branching leafy sprays.

The whole design of the carpet is made up of the group C and the surrounding figures D E a b d, together with the branching twigs and sprays, which join the groups and figures and 35 fill the interstices between them.
